[57] CLAIM

The ornamental design for an insect control lamp, as shown and described.

DESCRIPTION

FIG. 1 is a front perspective view from above and to one side of an insect control lamp showing the new design.

FIG. 2 is a front elevational view of the lamp of FIG. 1, the back and left and right elevational views being identical thereto.

FIG. 3 is a top plan view of the lamp of FIG. 1; and,
FIG. 4 is a bottom plan view of the lamp of FIG. 1.

The features interior to the lamp and visible from above, seen in FIG. 3, form no part of the claimed design.
